UNITED STATES PATENT OFFICE.

JOHANNA C. SAMUEL, OF NEW YORK, N. Y.

DESIGN FOR A LIFE-PRESERVER.

SPECIFICATION forming part of Design No. 26,956, dated April 20, 1897.

Application filed March 10, 1897. Serial No. 626,884. Term of patent 14 years.

To all whom it may concern:

Be it known that I, JOHANNA C. SAMUEL, a citizen of the United States, residing at New York, in the county of New York and State of New York, have invented and produced a new and original Design for Life-Preservers; and I do declare the following to be a full, clear, and exact description of the same, reference being had to the accompanying drawing, forming a part thereof.

My invention relates to a design for an inflatable life-preserver.

It relates to the entire configuration of the life-preserver, and especially to a life-preserver formed of rubber, celluloid, oil-silk, or white cotton or linen made waterproof and air-tight.

My invention relates particularly to a design for a life-preserver as illustrated in the accompanying drawing, in which the figure in the drawing is a perspective view of a life-preserver embodying my design.

The leading features of my design appear in the following description:

A flexible belt is employed for encompass-

ing the body, and from the rear portion of said belt two vertical parallel wings or blades project, as shown. The point of junction of the base of the wings or blades with the band or belt is enlarged to form chambers, and they are embossed, as shown, and from this enlarged base portion a series of radiating ribs extend outwardly to the semicircular scalloped edge of the wings. The upper and lower edges of these wings terminate in acute-angled points, and from each pointed end a crescent-shaped cylindrical rib extends to the base.

Having thus fully described my invention, what I claim as new and useful, and desire to secure by Letters Patent, is—

The design for a life-preserver, substantially as herein shown and described.

In testimony whereof I affix my signature in presence of two witnesses.

JOHANNA C. SAMUEL.
